UNITED STATES PATENT OFFICE.

HENRY HANSEN, OF WOODBINE, AND JEROME OTTO SMITH, OF DUNLAP, IOWA.

GEARING FOR HOISTING APPARATUS.

1,245,225.

Specification of Letters Patent.

Patented Nov. 6, 1917.

Application filed February 16, 1916. Serial No. 78,639.

To all whom it may concern:

Be it known that we, HENRY HANSEN and JEROME OTTO SMITH, both citizens of the United States, and residents of Woodbine and Dunlap, respectively, in the county of Harrison and State of Iowa, have invented a new and Improved Gearing for Hoisting Apparatus, of which the following is a full, clear, and exact description:

10 Our invention is intended more particularly for embodiment in a machine involving the use of a crane and bucket and adapted to be employed for various purposes, such as digging, loading manure, hoisting, or as 15 a hay stacker.

The various objects and advantages of the invention will more particularly appear as the description proceeds.

Reference is to be had to the accompanying drawings forming a part of this specification in which similar reference characters indicate corresponding parts in all the views.

Figure 1 is a side elevation of a machine embodying our invention with parts broken 25 away;

Fig. 2 is an enlarged transverse vertical section on the line 2--2, Fig. 1;

Fig. 3 is a detail transverse vertical section on the line 5--5, Fig. 1;

30 Fig. 4 is a horizontal section on the line 6--6, Fig. 1.

In constructing a machine embodying our invention, a platform 10 is provided desirably having an axle 11 for mounting running wheels 12 and having any suitable provision 13 for the connection of a draft tongue.

40 A suitable frame 14 is erected on the platform 10 and in said frame is mounted a post or mast 15 of a crane, said post having, in the example shown, a set collar 16 resting on a head 17 on the frame 14. The post 15 turns in a suitable bearing 18 in the head 17 and in a lower bearing 18^a secured to 45 frame members 19.

The jib or arm 20 of the crane suspends a bucket or skip 21, the cable 22 of which is secured at one end to said arm 20 and runs over sheaves, 23, 24, on the bucket and 50 over either of two sheaves, 25, 26, on the arm 20 and thence over a standing sheave 27 at the top of the post 15, through which post the cable extends downwardly to a drum 28 on the platform 10.

55 The numeral 29 indicates a suitable engine on the platform 10, the shaft of which turns

the main drive shaft 31 through any suitable means such as a belt 30. On the shaft 31 is a loose barrel pinion 32, and driving connection between the said shaft 31 and pinion 32 is controlled by any suitable clutch 33 and clutch lever 34, the clutch being held in engagement by a spring 35. The loose pinion 32 is in constant mesh with a gear wheel 36 on the shaft 37 of the drum 28. 60 65

The drum 28 is controlled by the following means, best shown in Fig. 4. The said drum is loose on the shaft 37 and mating clutch teeth 38 are provided on the said drum and on the gear wheel 36. A yoke 39 embraces the drum and is pivotally mounted at each end thereof, there being a collar 40 on said yoke at one end of the drum and a collar 41 at the opposite end embracing the meeting ends of the drum 28 and gear wheel 36 and encircling the clutch teeth 38. A spring 42 on the shaft 37 normally tends to engage the clutch teeth 38. To disengage said clutch teeth a clutch lever 43 is pivoted on the yoke 39 as at 44 80 for horizontal movement and has at one side a nose 45 adapted to bear against the inner face of the fast gear wheel 36. A brake band 46 embraces the hub 47 of the drum 28, said band being secured at one end to 85 the yoke 39 and at its opposite end to a post 46^a or other fixed member on the frame or platform. By the described construction the clutch lever 43 may be rocked laterally to press the nose 45 against the gear wheel 36 and thereby shift the drum 28 longitudinally of the shaft 37 against the action of the spring 42 and thereby disengage the clutch teeth 38. The lever 43 may then be vibrated vertically to control the brake 90 band 46. 95

On the shaft 31 is a pinion 48 in mesh with a similar pinion 49 on a counter-shaft 50 and on said shafts 31 and 50 are worms, 51, 52, which, by reason of the pinions, 48, 49, will turn in opposite directions. Either of the said worms is adapted to have driving engagement with a worm wheel 53 on a sliding collar 54 on the lower end of the post 15, said collar being adapted to be 100 shifted by a lever 55 through links 56, whereby to throw said worm wheel 53 into driving engagement with either of the worms, 51, 52, for turning the post 15 in either direction. In operation the clutch lever 34 110 may be thrown to disestablish driving connection between the drum gear 36 and the

engine. Also, when the drum is being driven to hoist a load or to direct the bucket 21, the clutch lever 43 may be thrown to throw the drum out of driving engagement with its gear wheel 36 and the drum then controlled through the said lever 43 and brake band 46. The post may be turned in either direction to dispose a raised load in proper position through the medium of the lever 55 and the consequent raising and lowering of the worm wheel 53.

The rigging of the cable 22 in Fig. 1 is for hoisting and lowering. In said figure, it will be observed that the end of the cable is made fast to the jib 20 at an eye 56 on said jib and runs thence to the sheave 23, to the sheave 24, and then upwardly over the sheave 25 on said jib to the sheave 27.

The rigging in Fig. 3 is for using the bucket 21 as a drag in ditching or excavating. In this latter arrangement the end of the cable is made fast to an eye 57, or the like, on the jib 20 inward from the eye 56 and thence downwardly about the sheaves 23, 24, on the bucket and thence over the sheave 26, which is positioned on the jib 20 outward from the eye 57. It will thus be seen that in the rigging in Fig. 1 the bucket is disposed outwardly while in the rigging in Fig. 3, the nose of the bucket is disposed inwardly for dragging the same toward the crane. The bucket has suitable handles 59 for manual guiding. The cable 22 has a stop 60 thereon that may be variously positioned by a set screw 61.

In transporting the machine, the bucket is adapted to be carried on the platform 10 and provision is made for swinging the post 15 downwardly to approximately a horizontal position. Any suitable means may be provided for permitting the pivotal movement of the post 15 in the vertical plane and for sustaining it firmly in an erect position. An expedient for this purpose may consist of studs 62 (Fig. 3), on opposite sides of the bearing 18 and extending through the head

or box 17. The said studs 62 have nuts 63. An auxiliary bearing sleeve 18^b in the head 17 below the bearing 18 is adapted to receive bolts or set screws 64 which are removed when the post is to be swung downwardly on the pivots 62. To permit the swinging of the lower end of the post 15, the bearing 18^a is detachably secured to the frame member 19, said bearing having a flange 65 for the purpose which is secured by bolts 66. To permit a swinging of the post also, the connection of the collar 54 with the lever 55 is broken by detaching any of the link connections as at 67. In any event, the removal of only a few bolts is necessary to swing the post to the lowered position.

The various shafts have bearings in suitable frame members, indicated generally by the character 14^a.

As best seen in Fig. 4, the sheaves, 23, 24, are disposed in tandem on the bucket 21 on a forwardly projecting arm overhanging the scoop, said arm consisting of converging side members 21^a and intermediate frame members 21^b provided with cheeks 21^c, 21^d, for the respective sheaves.

Having thus described our invention we claim as new and desire to secure by Letters Patent:

A machine of the class described including a mast mounted to turn, a drive shaft, a counter-shaft geared with the drive shaft, worms on said drive shaft and counter-shaft, a worm wheel movable vertically on the mast to engage with either of said worms or to a neutral position and adapted to turn the mast about its vertical axis, and means to raise and lower said worm wheel.

In testimony whereof we have signed our names to this specification in the presence of two subscribing witnesses.

HENRY HANSEN.
J. OTTO SMITH.
